UNITED STATES PATENT OFFICE.

HOWARD KELTY, OF FRANKTOWN, COLORADO.

STOVE-MAT.

1,072,333.

Specification of Letters Patent. Patented Sept. 2, 1913.

Application filed February 14, 1913. Serial No. 748,433.

To all whom it may concern:

Be it known that I, HOWARD KELTY, a citizen of the United States, residing at Franktown, in the county of Douglas and 5 State of Colorado, have invented new and useful Improvements in Stove-Mats, of which the following is a specification.

This invention relates to certain novel and useful improvements in ash mats or 10 bases for heating stoves.

In carrying out the present invention, it is my purpose to provide a mat or base piece for supporting a heating stove and by means of which the transmission of heat 15 from the lower portion of the stove to the floor will be avoided, and ashes prevented from falling on the floor or the mat, when withdrawing the ash pan from the ash pit of the stove.

20 It is also my purpose to provide a stove base platform or mat which will embrace the desired features of simplicity, efficiency, durability and convenience coupled with cheapness of cost in manufacture and 25 marketing and which may be readily applied beneath any stove.

With the above and other objects in view, the invention consists in the construction, combination and arrangement of parts here- 30 inafter set forth in and falling within the scope of the claims.

In the accompanying drawing; Figure 1 is a view in front elevation of a mat or platform constructed in accordance with 35 my present invention showing a stove positioned upon the same. Fig. 2 is a top plan view of the mat or platform, and Fig. 3 is a sectional view therethrough.

Referring now to the accompanying 40 drawing in detail, the numeral 1 indicates a stove mat which is adapted to be positioned upon the floor and is constructed of any suitable or desired material. This mat may be of any appropriate size and is 45 adapted to receive the legs of a heating stove 2, the latter resting upon the mat.

The numeral 3 indicates a substantially rectangular casing or housing built upon the mat 1 at the center thereof and immediately

below the bottom wall of the ash pit of the 50 heating stove 2, such housing having an open end 4 designed to slidably receive a drawer 5. This drawer, it will be noted is of a width greater than that of the opening to the ash pit and consequently greater than 55 the width of the pan in the ash pit. Thus, when it is desired to withdraw the ash pan from the pit, the drawer 5 in the housing 3 is moved to an open position and disposed below the edge of the base of the stove 60 thereby catching any ashes which may fall from the pan. The housing 3 of the drawer constitutes a baffle plate whereby transmission of the heat from the bottom of the stove to the mat or the floor is eliminated. 65

It will be seen that I have provided a protector for stoves whereby the transmission of heat from the stove to the floor is eliminated and by means of which ashes falling from the ash pan are caught thereby avoid- 70 ing the inconvenience of sweeping.

I claim:

1. A protector for stoves or the like comprising a mat, a housing built upon the mat approximately centrally thereof and having 75 an open end, and a drawer slidably into and out of the housing by way of the open end thereof substantially as, and for the purpose, set forth.

2. The combination with a stove, of a pro- 80 tector therefor comprising a mat upon which the stove is adapted to rest, a housing built upon the mat approximately centrally 85 thereof between the upper surface of the mat and the base of the stove to form a deflector whereby the transmission of heat from the stove to the mat and floor is avoided, said casing having an open end, and a drawer slidably into and out of the casing by way of the open end thereof and of a 90 width greater than that of the opening to the ash pit of the stove.

In testimony whereof I affix my signature in presence of two witnesses.

HOWARD KELTY.
